US00D869351S

(12) **United States Design Patent** (10) Patent No.: **US D869,351 S**
(45) Date of Patent: **** Dec. 10, 2019**

(54) **GRILLE SURROUND**

(71) Applicants: **Jonathan S. Duncan**, Seattle, WA (US); **Amanda Koh**, Kenmore, WA (US); **Peter Vurpillat**, Seattle, WA (US); **Chris Small**, Seattle, WA (US); **John Jackson**, Sammamish, WA (US); **Rebecca Kern**, Kent, WA (US)

(72) Inventors: **Jonathan S. Duncan**, Seattle, WA (US); **Amanda Koh**, Kenmore, WA (US); **Peter Vurpillat**, Seattle, WA (US); **Chris Small**, Seattle, WA (US); **John Jackson**, Sammamish, WA (US); **Rebecca Kern**, Kent, WA (US)

(73) Assignee: **PACCAR INC**, Bellevue, WA (US)(**) Term: **15 Years**(21) Appl. No.: **29/644,072**(22) Filed: **Apr. 13, 2018**(51) LOC (12) Cl. **12-16**

(52) U.S. Cl.

(57) **CLAIM**

The ornamental design for a grille surround, as shown and described.

DESCRIPTION

FIG. 1 is a perspective view of a grille surround showing our new design;

FIG. 2 is a front view of the grille surround shown in FIG. 1;

FIG. 3 is a top view of the grille surround shown in FIG. 1; FIG. 4 is a right side view of the grille surround shown in FIG. 1; and,

FIG. 5 is a left side view of the grille surround shown in FIG. 1.

The broken lines in the drawings depict portions of the grille surround that form no part of the claimed design.
